ATTORNEYS.

UNITED STATES PATENT OFFICE.

FRANCIS G. DAVIS, OF WATERTOWN, NEW YORK.

DESIGN FOR A CAB FOR AN AUTOTRUCK.

57,186.

Specification for Design.

Patented Mar. 1, 1921.

Application filed March 5, 1919. Serial No. 280,863. Term of patent 7 years.

To all whom it may concern:

Be it known that I, FRANCIS G. DAVIS, a citizen of the United States, residing at Watertown, New York, have invented and produced a new, original, and ornamental Design for Cabs for Autotrucks, of which the following is a specification, reference being had to the accompanying drawings, forming a part thereof.

Figure 1, shows a front view of the cab.

Fig. 2 is substantially a side view thereof.
Fig. 3 is a perspective view thereof.

I claim:

The ornamental design for a cab for an auto truck as shown and described.

FRANCIS G. DAVIS.
